(57) **ABSTRACT**

A new *Verbena* plant named 'VEAZ0029' particularly distinguished by its medium sized inflorescences, medium sized flowers that are real white, medium green, undivided leaves, and an upright plant habit.

1 Drawing Sheet

1

Latin name of the genus and species of the plant claimed:
Verbena hybrida.

Varietal denomination: 'VEAZ0029'.

BACKGROUND OF THE NEW PLANT

The present invention comprises a new *Verbena*, botanically known as *Verbena hybrida*, and hereinafter referred to by the variety name 'VEAZ0029'.

'VEAZ0029' is a product of a planned breeding program. The new cultivar has medium sized inflorescences, medium sized flowers that are real white, medium green, undivided leaves, and an upright plant habit.

'VEAZ0029' originated from an open pollinated cross made in July 2010 in the field in Enkhuizen, The Netherlands.

The female parent was an unpatented proprietary plant designated 'N0563-5', having a purple with white eye flower color, small leaves, and an upright plant habit.

The resulting seed was sown in February 2011 in a greenhouse in Enkhuizen, The Netherlands. 'VEAZ0029' was selected as one flowering plant within the progeny of the stated cross in May 2011.

The first act of asexual reproduction of 'VEAZ0029' was accomplished when vegetative cuttings were propagated from the initial selection in June 2011 in a greenhouse in Enkhuizen, The Netherlands.

BRIEF SUMMARY OF INVENTION

Horticultural examination of plants grown from cuttings of the plant initiated in the fall of 2011, and continuing

2

thereafter, has demonstrated that the combination of characteristics as herein disclosed for 'VEAZ0029' are firmly fixed and are retained through successive generations of asexual reproduction.

5 'VEAZ0029' has not been observed under all possible environmental conditions. The phenotype may vary significantly with variations in environment such as temperature, light intensity, and day length.

A Plant Breeder's Right for this cultivar was applied for 10 in Canada on Feb. 18, 2015, No. 15-8532.

The following traits have been repeatedly observed and are determined to be basic characteristics of the new variety. The combination of these characteristics distinguishes this 15 *Verbena* as a new and distinct variety.

BRIEF DESCRIPTION OF THE PHOTOGRAPHS

The accompanying photographic drawings show typical flower and foliage characteristics of 'VEAZ0029' with colors being as true as possible with an illustration of this type.

The photographic drawing in FIG. 1 shows a close view of an inflorescence of the new plant, and in

FIG. 2 a whole flowering plant.

The aforementioned photographs were taken on Apr. 20, 2015 in Andijk, The Netherlands. The plants were about 10 weeks old and were grown in 12 cm pots.
